DEVELOPERS FOR PHOTOGRAPHIC SILVER HALIDE PAPERS

Ernst Tausch, Berlin-Charlottenburg, Germany, assignor to Photographica G. m. b. H., Berlin-Charlottenburg, Germany, a corporation of Germany

No Drawing. Application April 8, 1953,
Serial No. 347,603

Claims priority, application Germany April 10, 1952

5 Claims. (Cl. 96—66)

This invention relates to new developers for the treatment of photographic silver halide papers.

It is known that under unfavorable conditions photographic papers incline to produce a yellowish fog, mainly consisting of colloidal silver. Also the oxidation products of the developing agents may cause a similar yellowish discoloration of the layer and the support of photographic papers if the developer is exhausted and colored brown. A yellowish or off-white tint of the photographic prints also may be caused by a not pure white color of the paper support itself.

The mentioned discolorations are caused by an absorption of light in the short-wave part of the visible spectrum between about 4000 Å. and about 5500 Å. According to the present invention these discolorations are inhibited by special additions to the developers which cause on the papers treated therein a fluorescent effect in the same part of the spectrum. For this purpose the developers contain colorless or nearly colorless organic compounds which absorb ultraviolet light between about 2500 Å. and about 4000 Å. and emit visible light between about 4000 Å. and about 5500 Å. and which attach themselves in a substantive manner to the paper or its layers. In consequence of the fluorescent effect of said compounds in the developers the yellowish discoloration of the photographic papers is compensated and the prints show a purer and brighter white.

It is already known, that textiles and papers are treated to brighten their whites with fluorescent organic compounds, so called "optical bleaching agents." For photographic papers such compounds are proposed for the same purpose as additions to the layers. It was found, that it is much better for various reasons, to use these compounds in developers for photographic papers. Thus said compounds cannot affect the properties of the photographic layers, which are very sensitive in this regard especially during storage. Many of said compounds which cannot be added in technical pure form to the photographic layers may be used so in the developers. Also there are more possibilities when using the fluorescent compounds in the developers to get best suited effects for the prints by additions chosen optimally by kind and quantity, as if the layers of the photographic papers would already contain such a compound.

It was surprising and not to be foreseen, that said fluorescent organic compounds without injury of their efficiency could be added to the developers, since it is the usual practice to remove "optical bleaching agents" from textiles by treatment with soda solution. It was found, that the said fluorescent organic compounds can be used without trouble if they were chosen in the right manner and quantity.

Fluorescent organic compounds which can be used according to the present invention as additions to the developers for photographic papers, have been described in the literature. Especially suited for this purpose are,

2

for example, the derivatives of the 4,4'-diaminostilbene-2,2'-disulfonic acid according to the following formula:

in which Me represents a substituent selected from the group consisting of alkali metal, alkali earth metal, ammonium and substituted ammonium, while A_1 and A_2 may be the same and each represents a substituent selected from the group consisting of $-\text{CO}\cdot\text{R}_1$,

and

wherein R_1 represents a substituent selected from the group consisting of aryl and substituted aryl, R_2 represents a substituent selected from the group consisting of hydrogen, alkyl, aryl and substituted aryl, R_3 represents an amine residue, and R_4 represents a substituent selected from the group consisting of Cl, OH, NH_2 and an amine residue.

Symmetrical compounds according to this formula are:

I. 4,4-di-[acylamino]-stilbenes

II. 4,4-di-[ureido]-stilbenes

III. 4,4-di-[triazin-(1",3",5")-yl-(2")-amino]-stilbenes

Also according to this formula are unsymmetrical stilbene derivatives, described in the literature, which may be obtained from the 4-nitro-4'-aminostilbene-2,2'-disulfonic acid, e. g. 4-[ureido]-4'-[acylamino]-stilbenes or 4-[triazin-(1",3",5")-yl-(2")-amino]-4'-[acylamino]-stilbenes.

Suitable compounds are, for example:

- (1) Sodium 4,4'-di-(benzamido)-stilbene-2,2'-disulfonate
- (2) Sodium 4,4'-di-(p-aminobenzamido)-stilbene-2,2'-disulfonate
- (3) Sodium 4,4'-di-(p-acetaminobenzamido)-stilbene-2,2'-disulfonate
- (4) Sodium 4,4'-di-(2,5-dimethoxybenzamido)-stilbene-2,2'-disulfonate
- (5) Sodium 4,4'-di-(p-methylaminobenzamido)-stilbene-2,2'-disulfonate
- (6) Sodium 4,4'-di-(methylureido)-stilbene-2,2'-disulfonate
- (7) Sodium 4,4'-di-(phenylureido)-stilbene-2,2'-disulfonate
- (8) Sodium 4,4'-di-(p-tolylureido)-stilbene-2,2'-disulfonate
- (9) Sodium 4,4'-di-(p-chlorphenylureido)-stilbene-2,2'-disulfonate

- (10) Sodium 4,4'-di-(p-ethanolamino-phenylureido)-stilbene-2,2'-disulfonate
- (11) Sodium 4,4'-di-[4"-hydroxy-6"-anilino-triazin-(1", 3", 5")-yl-(2")-amino]-stilbene-2,2'-disulfonate
- (12) Sodium 4,4'-di-[4"-hydroxy-6"-amino-triazin-(1", 3", 5")-yl-(2")-amino]-stilbene-2,2'-disulfonate
- (13) Sodium 4,4'-di-[4", 6"-di-ethanolamino-triazin-(1", 3", 5")-yl-(2")-amino]-stilbene-2,2'-disulfonate
- (14) Sodium 4,4'-di-[4"-ethanolamino-6"-anilino-triazin-(1", 3", 5")-yl-(2")-amino]-stilbene-2,2'-disulfonate
- (15) Sodium 4,4'-di-[4"-dimethylamino-6"-anilino-triazin-(1", 3", 5")-yl-(2")-amino]-stilbene-2,2'-disulfonate
- (16) Sodium 4-acetamino-4'-[4", 6"-di-methylamino-triazin-(1", 3", 5")-yl-(2")-amino]-stilbene-2,2'-disulfonate
- (17) Sodium 4-phenylacetamino-4'-[4", 6"-diamino-triazin-(1", 3", 5")-yl-(2")-amino]-stilbene-2,2'-disulfonate
- (18) Sodium 4-acetamino-4'-[phenylureido]-stilbene-2,2'-disulfonate
- (19) Sodium 4-(2"-ethoxy-4"-methyl-benzamido)-4'-[phenylureido]-stilbene-2,2'-disulfonate

It should be emphasized, that the said compounds themselves are not the subject of the present invention; since they do not limit the fluorescent organic compounds suited as additions according to this invention to developers for photographic papers, they are mentioned as examples only.

The above-mentioned compounds have the mutual property to attach themselves in a substantive manner to the support and the layers of the photographic papers.

As developers for photographic papers which according to the present invention can be improved by addition of fluorescent organic compounds, all kinds of developers may be cited which normally are used between exposure and drying for the treatment of photographic silver halide papers. Developers according to this invention have special advantages for papers designed for use in connection with color photography, in particular multi-layer color papers. The present invention will be illustrated by the following examples without limiting it by the discussed cases:

Example 1

To a paper developer of the composition:

	Grams
p-Methylaminophenol sulfate	1
Sodium sulfite (desicc.)	12
Hydroquinone	3
Sodium carbonate (desicc.)	24
Potassium bromide	1
Water to 1000 ccm.	

is added 0.2 g. of sodium 4,4'-di-(phenylureido)-stilbene-2,2'-disulfonate. It produces photographic prints with much purer and brighter whites than the same developer without this addition. The other properties of the developer will not be changed by the addition.

Example 2

To a manufactured paper developer of the composition:

	Grams
I. p-methylaminophenol sulfate	15
Hydroquinone	60
II. Sodium sulfite (desicc.)	225
Sodium carbonate (desicc.)	340
Potassium bromide	10

is added (in II) 2.5 g. sodium 4,4'-di-[4"-hydroxy-6"-anilino-triazin-(1", 3", 5")-yl-(2")-amino]-stilbene-2,2'-disulfonate.

I and II were dissolved successively in 5 lit. of water. In use, 1 part developer is diluted with 2 parts of water.

This developer produces with all kinds of photographic papers purer and brighter whites than the same developer without the addition according to this invention.

Example 3

To a color developer of the composition:

	Grams
p-Diethylaminoanilin sulfate	4
10 Sodium sulfite (desicc.)	1
Potassium carbonate	75
Potassium bromide	0.5
Water to 1000 ccm.	

is added 0.2 g. of the same stilbene derivate as in Example 2. It produces a better white at the development of the color-prints on multilayer-color papers than without the addition.

Various changes and modifications may be made without departing from the spirit and scope of the present invention and it is intended that such obvious changes and modifications be embraced by the annexed claims.

Having thus described the invention, what is claimed as new and desired to be secured by Letters Patent, is:

1. In the process of producing photographic images with improved whiteness, the step of processing exposed light-sensitive silver halide-coated papers with a silver halide developer having dissolved therein a substantially colorless derivative of 4,4'-diamino-stilbene-2,2'-disulphonic acid, said derivative absorbing ultraviolet radiation of between about 3,000 Angstrom units and 4,000 Angstrom units and emitting fluorescent light of between about 4,000 Angstrom units and 5,500 Angstrom units and having the formula:

35

in which Me represents a substituent selected from the group consisting of alkali metal, alkali earth metal and ammonium, while A₁ and A₂ each represents a substituent selected from the group consisting of —CO·R₁, —CO—NH·R₂ and

45

wherein R₁ represents aryl, R₂ represents a substituent selected from the group consisting of hydrogen, alkyl and aryl, R₃ represents amino, and R₄ represents a substituent selected from the group consisting of Cl, OH and amino.

2. The process according to claim 1, wherein the derivative of 4,4'-diamino-stilbene-2,2'-disulphonic acid is the sodium salt of 4,4'-di-(phenylureido)-stilbene-2,2'-disulphonic acid.

3. The process according to claim 2, said sodium salt of 4,4'-di-(phenylureido)-stilbene-2,2'-disulphonic acid being present in an amount ranging between about 0.05 and 1.0 gram per liter of developer.

4. The process according to claim 1, wherein the derivative of 4,4'-diamino-stilbene-2,2'-disulphonic acid is the sodium salt of 4,4'-di-[4"-hydroxy-6"-anilino-triazin-(1", 3", 5")-yl-(2")-amino]-stilbene-2,2'-disulphonic acid.

5. The process according to claim 4, said sodium salt of 4,4'-di-[4"-hydroxy-6"-anilino-triazin-(1", 3", 5")-yl-(2")-amino]-stilbene-2,2'-disulphonic acid being present in an amount ranging between about 0.05 and 1.0 gram per liter of developer.
